DRIVING MEANS FOR PROVIDING CYCLIC VARIATIONS OF SPEED

George Stephen Kammer, Park Lane, London,
EnglandApplication February 21, 1940, Serial No. 320,218
In Great Britain March 7, 1939

7 Claims. (Cl. 74—394)

The invention relates to driving means for providing a cyclic variation of speed. Although it has been devised primarily for application to sleeve valve engines for the purpose of moving the sleeve valve for opening and closing the ports, it will be readily understood that it may have other applications in practice such as to driving poppet valves in internal combustion engines or to shuttle races in wide looms, or in fact to any case in which an oscillating element is to be held nearly stationary at one extreme position or where the speed of movement is required to be substantially higher near one end of travel than the other.

In the specification of British Patent No. 506,- 326 I have described and claimed a mechanism for imparting to a sleeve valve the appropriate movements in the axial and peripheral directions to ensure more satisfactory conditions of port opening and closing than usually provided hitherto. A form of port was described and claimed in the specification of British Patent No. 511,479 which was particularly suitable for valves operated by gear of this kind.

The present invention provides an alternative form of drive for the sleeve. The sleeve is operably driven by the usual well-known gear comprising an overhung crank shaft and a pin positively connected to the valve and engaged by the crank, the motion being derived from the engine shaft. According to the invention the driving means comprises a pair of gear wheels with preferably equal numbers of teeth but mounted on shafts eccentric to their peripheries. The pitch lines of the gears are circular and the eccentricities may be equal or unequal, the wheels being preferably so set that the furthest point of one wheel from the centre engages the nearest point of the other and vice versa. The gear wheels are held in correct engagement by a yoke or link having bearings concentric with the pitch lines of the wheels. When used for driving a sleeve valve the ports are then opened and closed rapidly, while the movement of the sleeve is comparatively slow during the time when the ports are closed.

Eccentric gears have already been proposed, but the pitch lines were other than circular. It is still impossible in practice to manufacture oval gears of this kind which will operate satisfactorily at high speeds of revolution, since suitable gear cutting machinery has not been devised. Such gears are restricted to comparatively low speeds of a few hundred revolutions per minute.

The accompanying drawings show a form of construction according to the invention as ap-

plied to a sleeve valve internal combustion engine, and therein

Figure 1 is a sectional elevation through the driving mechanism and associated parts,

Figure 2 is an exploded perspective view of the gears and yoke, and

Figures 3a to 3k constitute a set of diagrams to show the operation.

Referring to Figure 1 the crank shaft 1 and connecting rod 2 are shown broken away. Part of the sleeve valve 3 of the Burt McCollum type with ports 4 is also indicated. A gear wheel 5 keyed on the shaft 1 drives a gear wheel 6 journalled on a stationary shaft 7. The shaft 7 is supported at one end in the crank case 21 and is fixed at the other end to an end cover 22 attached to the crank case 21 and removable for access to the gearing. The gear wheels 5 and 6 are ordinary circular gears.

The gear wheel 6 is attached by screws 23 to a circular gear wheel 8 running eccentrically on the shaft 7 by means of roller bearings 24. The gear wheel 8 meshes with a second gear wheel 9 having the same number of teeth. The gear wheel 8 has short hubs 10 and 11 concentric with its pitch line, and the gear wheel 9 similarly has short hubs 12 and 13.

Two yokes 15, seen better in Figure 2, are journalled on the hubs 10, 11, 12 and 13 by means of roller bearings 14. The yokes keep the gear wheels in correct engagement at all times. A shaft 16 projects outwards from the gear wheel 9 parallel to the shaft 7, and a roller 17 journalled on the shaft 16 by roller bearings engages the internal faces of a vertical slide 18 formed on the inside of the cover 22. The position of attachment of the shaft 16 on the gear 9 is determined by the required eccentricity of the gear.

The gear wheel 9 is formed with a socket 25 in which a slider 26 can move parallel to the axis of the gear. The slider has a spherical seating to engage a spherical member 19 mounted on a pin 20, which is attached to the sleeve 3.

In operation the gear wheel 6 is driven at a uniform speed and with it the gear wheel 8. On account of the eccentricities of the gear wheels 8 and 9 the latter rotates at a speed varying throughout one revolution but repeating its variation in a similar manner at each revolution. The wheels 8 and 9 are held in mesh by the yokes 15, and, since the wheel 9 is constrained by the slides 18 acting on its shaft 16, the yokes will carry out an oscillation of the same period as the rotation of the gears. The pin 20 of the sleeve 3 will have a pronounced dwell at its upper dead centre while

moving rapidly through the lower part of its travel.

Figures 3a to 3k form a set of diagrams showing the movement obtained with a particular set of dimensions. The larger circles marked 8 and 9 represent the pitch circles of the gear wheels 8 and 9. The smaller circle inside 8 has its centre at P, the centre line of the shaft 7, and touches the circle 8 so as to indicate clearly the eccentricity of the latter. The smaller circle inside 9 similarly shows the eccentricity by having its centre at O, the centre line of the shaft 16, and by touching the circle 9.

If the mechanism has started with the centres of the circles 8 and 9 on the vertical line joining the centres O and P and the eccentricities both downwards, Figure 3a shows the position after the gear 8 has moved through an angle of 15° clockwise. The point C represents the axis of the socket 25 and consequently of the pin 20, and the movement of the point C in the various diagrams reproduces the movement of the sleeve.

Figures 3b and 3c show the position after 30° and 45° rotation of the gear 8 respectively. It will be noted that although the point C has moved a little to the left, representing a rotation of the sleeve on its axis, the vertical position of the point has remained unaltered. Even in Figure 3d showing the position after 60° movement of 8 the downward movement of the point C is barely perceptible on the scale of the drawings.

Figure 3e showing the position after 75° rotation of 8 gives the first appreciable downward movement of the point C, viz. 2.5 units. This measurement is based on gears 8 and 9 having pitch line diameters of 60 units each and eccentricities of 10 units each, and a throw of 20 units for the point C, i. e. a total vertical travel of 40 units.

After 90° movement of the wheel 8 a sinusoidal drive would give a vertical movement of 20 units for the point C, whereas Figure 3f shows that the actual movement is only a quarter of this amount, viz. 5 units. After this point the vertical movement gradually becomes more rapid. Figure 3g shows a movement of 8 units for 105°, Figure 3h one of 13.5 units for 120° and Figure 3i one of 20.8 units for 135°. Actually with the proportions used as a basis for Figures 3a to 3k the half way position of 20 units is reached after a rotation of the wheel 8 through 132° 30'.

Figure 3k shows a continuation of the rapid downward movement of the point C which has here reached 28 units with 150° rotation of the wheel 8. The position at 165° will be clear without a diagram and at 180° the point C reaches its lower dead centre at 40 units. Thereafter the upward movement of the point C is similar, reaching a point within 5 units of its top position at an angular movement of 270° corresponding to Figure 3f.

The operation of the gear may be summed up by saying that the true axis of the gear 8 carries out a rotary movement about the axis P and that of the gear 9 about the axis O. The axis O is as shown in Figures 1 and 2 constrained to move up and down in a vertical plane and forms the axis of rotation for the pin 20 of the sleeve.

The speed characteristics can be varied by varying the eccentricity of either or both of the wheels 8 and 9 on their axes P and O. In an extreme case the pin 20 could be made to remain at its upper position for the greater part of a cycle and to carry out its travel downwards

and return within 100° of rotation of the wheel 8. This may not be of interest for driving sleeve valves in engines of the kind referred to, but could be advantageously applied to poppet valves. 5 The valves would then be positively driven in both directions, and the engine speed would no longer be limited by the operation of a spring return for the valves.

Although in the example described the axis O was caused to move directly towards and away from the axis P, this is not necessarily the case. The path of the axis O may be non-planar and such a movement may be effected by link gear attached to the shaft 16 or to a point on the yoke. The link gear may comprise a single link having its other end moved by an eccentric, so that an additional component of movement is impressed on the axis O.

What I claim is:

1. Driving means for providing a cyclic variation of speed between a driving member driven at constant speed and a driven member, comprising in combination a shaft driven by the driving member, a circular gear wheel mounted eccentrically on the said shaft, a second circular gear wheel, bearings on the gear wheels concentric with their respective pitch lines, a yoke engaging the said bearings to hold the gear wheels in mesh, a shaft attached eccentrically to the second gear wheel, constraining means to guide the second shaft in a predetermined path as the distance between the shaft axes varies, and means for imparting the movement of the second gear wheel to the driven member.

2. Driving means for providing a cyclic variation of speed between a driving member driven at constant speed and a driven member, comprising in combination a shaft driven by the driving member, a circular gear wheel mounted eccentrically on the said shaft, a second circular gear wheel having the same number of teeth as the first, bearings on the gear wheels concentric with their respective pitch lines, a yoke engaging the said bearings to hold the gear wheels in mesh, a shaft attached eccentrically to the second gear wheel, constraining means to guide the second shaft in a predetermined path as the distance between the shaft axes varies, and means for imparting the movement of the second gear wheel to the driven member.

3. Driving means for providing a cyclic variation of speed between a driving member driven at constant speed and a driven member, comprising in combination a shaft driven by the driving member, a circular gear wheel mounted eccentrically on the said shaft, a second circular gear wheel having the same number of teeth as the first, bearings on the gear wheels concentric with their respective pitch lines, a yoke engaging the said bearings to hold the gear wheels in mesh, a shaft attached to the second gear wheel with the same eccentricity as that of the first gear wheel on its shaft, constraining means to guide the second shaft in a predetermined path as the distance between the shaft axes varies, and means for imparting the movement of the second gear wheel to the driven member.

4. Driving means for providing a cyclic variation of speed between a driving member driven at constant speed and a driven member, comprising in combination a shaft driven by the driving member, a circular gear wheel mounted eccentrically on the said shaft, a second circular gear wheel having the same number of teeth as the first, bearings on the gear wheels concentric with

their respective pitch lines, a yoke engaging the said bearings to hold the gear wheels in mesh, a shaft attached to the second gear wheel with the same eccentricity as that of the first gear wheel on its shaft, constraining means to guide the second shaft in a predetermined path as the distance between the shaft axes varies, and means for imparting the movement of the second gear wheel to the driven member, the gear wheels being so set that the furthest point of one wheel from the axis of its shaft engages the nearest point of the other and vice versa.

5. Driving means for providing a cyclic variation of speed between a driving member driven at constant speed and a driven member, comprising in combination a shaft driven by the driving member, a circular gear wheel mounted eccentrically on the said shaft, a second circular gear wheel, bearings on the gear wheels concentric with their respective pitch lines, a yoke engaging the said bearings to hold the gear wheels in mesh, a shaft attached eccentrically to the second gear wheel, parallel guides to constrain the second shaft to move directly towards and away from the first shaft, and means for imparting the movement of the second gear wheel to the driven member.

6. Driving means for providing a cyclic variation of speed between a driving member driven at constant speed and a driven member, comprising

10

ing in combination a shaft driven by the driving member, a circular gear wheel mounted eccentrically on the said shaft, a second circular gear wheel, bearings on the gear wheels concentric with their respective pitch lines, a yoke engaging the said bearings to hold the gear wheels in mesh, a shaft attached eccentrically to the second gear wheel, constraining means to guide the second shaft in a predetermined path as the distance between the shaft axes varies, and a crank pin on the second gear wheel to actuate the driven member.

15

7. Driving means for providing a cyclic variation of speed between a driving member driven at constant speed and a driven member, comprising in combination a shaft driven by the driving member, a circular gear wheel mounted eccentrically on the said shaft, a second circular gear wheel, bearings on the gear wheels concentric with their respective pitch lines, a yoke engaging the said bearings to hold the gear wheels in mesh, a shaft attached eccentrically to the second gear wheel, constraining means to guide the second shaft in a predetermined path as the distance between the shaft axes varies, and a crank pin on the second gear wheel on the opposite side of the axis of the second shaft to the centre of the pitch line to actuate the driven member.
